CORNCOB HOLDER

Jean O. Reinecke, Chicago, Ill.

Application October 28, 1948, Serial No. 149,355

Term of patent 7 years

(Cl. D44—29)

To all whom it may concern:

Be it known that I, Jean O. Reinecke, a citizen of the United States, residing at Chicago, county of Cook, and State of Illinois, have invented a new, original, and ornamental Design for a Corn-cob Holder, of which the following is a specification, reference being had to the accompanying drawing, forming a part thereof, in which:

Figure 1 is a top plan view of a corncob holder, showing my new design; Fig. 2, a side view in elevation; Fig. 3, a front view in elevation; Fig. 4, a rear view in elevation; Fig. 5, a side view in elevation showing the side opposite to that shown in Fig. 2; and Fig. 6, a bottom plan view.

I claim:

The ornamental design for a corncob holder, as shown.

JEAN O. REINECKE.
